UNITED STATES PATENT OFFICE.

ALFRED ERNEST ARMITAGE, OF JUBILEE, NEW WESTMINSTER, BRITISH COLUMBIA,
CANADA.

PLUMBER'S JOINT-WIPING DEVICE.

Application filed November 9, 1926. Serial No. 147,318.

This invention relates to a device for wiping joints of lead pipes for use in plumbing work; its object is to systematize and simplify the labour of wiping joints, by providing mechanical means for performing work which is usually done by slow costly hand processes.

With modern standardized plumbing accessories which require a wiped lead joint there is a considerable proportion which can more easily and more cheaply be manufactured in the work-shop instead of in situ, and my device is intended to accelerate and cheapen the production of work of this kind.

To effect my improvements I use a device involving the following elements:—

A rectangular framework of the nature of a bench or table carries centrally disposed along and over its top, a mandrel or bar upon which are threaded and secured one or more lengths of lead pipe, brass ferrules or the like to be united. The bar is provided at suitable intervals with loose collars and cotter slots for securing the pieces of pipe or ferrules in any desired position. Means for holding the pieces in correct alignment centrally and longitudinally are also provided. Hingable bearings at intervals lengthwise of the mandrel enable the bar to be raised for the insertion of the work so that several joints may be wiped almost simultaneously.

Under each transverse division is arranged a slide having a motion rightangular to the bar and carrying a pivotal grooved member holding the wiping cloth and solder, so that the solder may be applied to the lead pipe at any angle and at any radius according to the position of the slide and the angle of the member holding the wiping cloth in relation to the bar. The mandrel is provided with a hand crank for slowly wiping the joints and has also a treadle device for rapidly trimming off the work.

In operation the device is used as follows: The work to be jointed and soldered is mounted upon the shaft 9 and there secured. The operator then takes hold of the pivotal solder holding wiper 19 and places same in contact with and on the underside of the joint to be wiped, the wiper 19 being held at an angle of about twenty degrees and a little towards the operator. Molten jointing metal is then poured over the joint at the same time as the work is

slowly revolved by the shaft 9 which is driven by either foot pedal or a helper. As the molten metal is poured over the joint it is wiped and formed into place by the manipulation of the wiper 19 being swiped (or struck with a sweeping motion) over the poured metal which quickly cools and hardens into place, the groove in the wiper block 19 giving to the finished joint the necessary reinforcement of metal as is usual in a hand-wiped joint of this character.

The work being centrally disposed over the bench all excess metal which escapes through the groove of the wiper block 19 before coming hardened is caught by the bench and can readily be replaced in the melting ladle free from all foreign substances, which is not the case when work of this character is performed out of the shop; therefore there is a saving both of metal and time by the use of this machine.

Referring to the drawings which form part of the application, Fig. 1 is a plan. Fig. 2 is a side elevation, Fig. 3 an end elevation, Fig. 4 a detail of the pipe holding device as applied at the end of the framework to an elbow. Fig. 5 is a sectional view of the pivotal solder holder, the two latter figures being to an enlarged scale.

Taking the drawings in detail these show a simple embodiment of my invention mounted upon a rectangular wood frame 6 of the nature of a table or stand, on the top side of which are secured three hingable bearings 7 carried by the transverse blocks 8. A shaft 9 of the nature of a mandrel is supported in the bearings 7, and is revolvable by the hand crank 10.

The framework is, for the convenient manipulation of the work, divided in three compartments 11, 12, 13. Immediately below the shaft in each compartment is a horizontally slid able member 14, 15, 16; the centre one being drawn out as shown at 15. Each of the slid able members carries a cranked spindle 17 which is free to pivot on the sides of the slid able members at 18 and carries in turn a pivotal solder-holder 19.

The method of securing the two pipes which are being united by a wiped lead joint at 20 is shown by the enlarged part sectional drawing Fig. 4 which also illustrates how a bend or elbow pipe 21 is manipulated, the usual brass ferrule or nipple 22 is held central about the shaft 9 by the adjustable cone 110

23, the latter being secured by the nut 24, 25 being a short length of pipe (shown in section) and acting as a distance piece between the cone 24 and the compressible washer 26, 5 also secured on the shaft by a nut 27.

A treadle 28 operates the lower crank-shaft 29 and the gear wheel 30 and pinion 31 in order to affect quick revolution of the shaft when the work is being cleaned off by 10 wire brush.

Having now particularly described my invention, what I desire to secure by Letters Patent, is:

1. A plumber's joint-wiping device comprising, a rectangular framework, a revolvable bar positioned above the top of said framework and supported therefrom, a plurality of hingable bearings carried by said framework and supporting said bar, means 15 for revolving said bar, a sliding member positioned below said bar and movable in said framework rightangularly to said bar, a cranked spindle carried by bearings in the sides of said sliding member, the axis of said 20 spindle being parallel to that of said bar, a solder-holding member pivotal on said 25 spindle, means for increasing the rotational speed of said bar, said means including a foot treadle, crank shaft and gear wheels.

2. A plumber's joint-wiping device comprising, a rectangular framework, a revolvable bar positioned above the top of said framework and supported therefrom, a plurality of hingable bearings carried by said framework and supporting said bar, means 30

for revolving said bar, a sliding member positioned below said bar and movable in 35 said framework rightangularly to said bar, a cranked spindle carried by bearings in the sides of said sliding member, the axis of said spindle being parallel to that of said bar, a solder-holding member pivotal on said 40 spindle, means for increasing the rotational speed of said bar, said means including a foot treadle, crank shaft and gear wheels.

3. A plumber's joint-wiping device comprising, a rectangular framework, a revolvable bar positioned above the top of said framework and supported therefrom, a plurality of hingable bearings carried by said framework and supporting said bar, means 45 for revolving said bar, a sliding member positioned below said bar and movable in said framework rightangularly to said bar, a cranked spindle carried by bearings in the sides of said sliding member, the axis of 50 said spindle being parallel to that of said bar, a solder-holding member pivotal on said 55 spindle, means for increasing the rotational speed of said bar, said means including a foot treadle, crank shaft and gear wheels, the said bar having an external screw thread 60 at one end, said bar having threaded thereon a truncated conical member, a distance piece, a compressible washer with nuts and washers for adjustment purposes.

In testimony whereof I affix my signature,
ALFRED ERNEST ARMITAGE.
